SEWING MACHINE

Casper J. Dorer, Cleveland, Ohio

Application March 31, 1933, Serial No. 663,723
Renewed January 28, 1937

2 Claims. (Cl. 112—218)

This invention relates to a sewing machine and particularly to the construction of the sewing machine head and hollow bracket arm or gooseneck.

5 It is desirable to provide in a sewing machine means for illuminating the work to enable the operator to observe fully at all times the operation of the needle bar and needle and the character of the stitches.

10 The principal object of the present invention is to provide in a sewing machine improved means for lighting the needle plate and the bed and operating members adjacent to said needle plate.

Another object is to provide lighting means for 15 a sewing machine, which while furnishing maximum illumination, does not reflect or shine in the eyes of the operator.

A further object is to provide in a sewing machine, lighting means which improves the appearance of the machine, occupies a minimum amount of space, is so positioned as to fully protect the light against damage and to afford no obstructions to the operator, and contains no loose or readily detachable parts which might 25 be lost, except, of course, the light bulb itself.

A still further object is to provide lighting means for a sewing machine, of such character that a separate reflector shield for the light bulb is not required.

30 A further object is to provide in the hollow bracket arm or gooseneck of a sewing machine, a housing chamber for an electric light bulb, whereby the light bulb is substantially enclosed by the hollow arm or gooseneck, without necessitating the formation of openings therein through which lubricant might pass outwardly thereof upon the work or through which dirt might enter to the detriment of the operative parts of the machine housed in the hollow arm or gooseneck.

40 A further object is to provide in the hollow bracket arm or gooseneck of a sewing machine, means for housing an electric light bulb which is of such form and character as to furnish increased reflecting surface as compared to the reflecting surface of the ordinary detachable shade or reflector.

45 Further and additional objects and advantages residing in the invention will become apparent hereinafter during the detailed description of an embodiment thereof which is illustrated in the accompanying drawing wherein:

50 Fig. 1 is a rear elevational view of a sewing machine head including the hollow bracket arm or gooseneck and the mounting bed therefor,

with certain portions of the head being indicated in dotted lines.

Fig. 2 is a sectional view taken substantially on line 2—2 of Fig. 1, looking in the direction of the arrows;

Fig. 3 is a sectional view taken substantially on line 3—3 of Fig. 2 looking in the direction of the arrows.

Fig. 4 is an end elevational view of the sewing machine head taken from the right-hand side 10 of Fig. 1.

Fig. 5 is a fragmentary sectional view taken substantially on line 5—5 of Fig. 1, looking in the direction of the arrows, and

Fig. 6 is a fragmentary sectional view taken substantially on line 6—6 of Fig. 2, looking in the direction of the arrows.

Referring to the drawing, and particularly to Figs. 1, 2 and 4, the sewing machine head includes a bed 10 which supports the hollow bracket 20 arm or gooseneck comprising a vertical member or standard 11 and a horizontal member 12 on the end of which is arranged the face 13. The face 13 has slidably mounted therein the usual presser bar 14 and reciprocating needle bar 15 25 carrying, respectively, a presser foot 16 and a needle 17, the latter operating through an opening in the needle plate, as is well understood in the art. The needle bar 15 is driven by suitable mechanism arranged in the face 13 and 30 operatively connected with the upper shaft 18 of the sewing machine, indicated in Figs. 1 and 4 in dotted lines and in Fig. 2 in section. The upper shaft 18 extends through the horizontal member of the hollow arm or gooseneck and is 35 operatively connected adjacent its left hand end, as viewed in Fig. 1, with suitable driving means and with a driving connection downwardly to the shuttle driving shaft and the feed bar rocking shaft arranged in the bed, but not illustrated 40 herein, since it forms, per se, no part of the present invention and is well understood in the art.

The hollow bracket arm or gooseneck is usually an integral casting and is provided interiorly 45 with bearing supports for the various shafts of the operating mechanism, and since such shafts and their bearings, together with the gearing on the shafts, are arranged or housed in the hollow bracket arm it is quite evident that it 50 will be necessary to introduce lubricant into the arm for the purpose of lubricating such operating parts.

It is highly desirable to provide a sewing machine with means for illuminating the work over 55

a wide area, which, of course, includes the part where the actual sewing operation takes place, as at the needle plate and the bed adjacent thereto. In providing such illuminating means it is important that the same be so constructed as to occupy as little space as possible and to offer no protruding or obstructive parts which would inconvenience the operator of the machine and detract from the appearance thereof.

10 The present invention contemplates illuminating or lighting means for a sewing machine, wherein said means may be built into the hollow bracket arm or gooseneck, so as to occupy a minimum amount of space, but without at the 15 same time forming openings into the interior of the hollow bracket arm, in which are housed the lubricated operative parts of the machine as previously stated.

10 In accomplishing this end, the horizontal member 20 of the hollow bracket arm is formed with an elongated recess or chamber 19 on its under side, by arching or offsetting the bottom wall 20 of the horizontal member upwardly substantially the depth of the chamber and curving the side 25 walls 21 outwardly and downwardly from the upwardly arched portion of the bottom wall 20. It will be seen that the recess or chamber 19, as thus provided, is located substantially within the external dimensions of horizontal member 12, but does not destroy the tubular character of the 30 member or provide any openings therein, and hence, no lubricant within the member can be thrown outwardly upon the work or can dirt or other foreign matter get into the hollow bracket and upon the operating mechanism contained 35 therein.

10 The recess or chamber 19 extends on the under side of the member 12 from adjacent the vertical member 11 toward the face 13 and beyond the 40 point where the member 12 commences to enlarge or flare outwardly to provide a bearing surface for the face 13, the deepest and widest portion of the recess or chamber being located substantially midway of its ends. It will be readily appreciated from the foregoing description and 45 from an inspection of Figs. 1 and 2 of the drawing, that the provision of the recess or chamber in the under side of the member 12 in this manner, rather than detracting from the appearance of the hollow bracket arm or gooseneck of the 50 sewing machine, actually improves the appearance thereof.

10 Although various ways of mounting an electric light bulb in the recess or chamber may be 55 employed, there is illustrated in the drawing a form of mounting for the light which possesses a certain advantages as will now be pointed out. A conduit 22 extends vertically adjacent the member 11 with its lower end passing through the bed 10 and its upper end extending into a tubular fitting 23 secured to the vertical member 11 of the hollow bracket arm by a suitable attaching screw 60 passing through a lug 24 and into a tapped opening in the member 11. The tubular fitting 23 is provided with an inwardly extending arm 25 lying 65 against the inner side of the vertical member 11, that is the right hand side of the member 11, as viewed in Fig. 1. The wall of the member 11 is provided with a cutaway portion 26 closed by 70 the fitting 23 and the arm 25 thereof, and into which from the conduit 22 extend wires 27 for the electric light.

10 The arm 25 is provided with an opening in which is fitted a suitable switch 28 operated by 75 the customary button lever 29 and clamped in

the opening by means of a nut 30 screwed upon the outwardly extending portion of the switch and engaging the enlarged circular end of a channeled supporting plate 31 fitting over the outwardly extending portion of the switch 28 and 5 arranged between the nut 30 and the inwardly extending arm 25 of the fitting 23. The channeled strip 31 is arranged so that its channel faces the vertical member 11 and has an intermediate angularly disposed portion such that its 10 outer end extends into the end of the recess 19 adjacent the vertical member 11. The end of the channel member 31, which extends into the recess or chamber, is provided with a threaded lateral extension 32 upon which is screwed a lamp 15 socket 33 for the electric light bulb 34. The wires 27, as previously mentioned, pass from the conduit 22 into the cutaway portion in the vertical member 11 that is closed by the fitting 23 and arm 25, and from there to the switch 28 from 20 whence they lead upwardly to the light socket within the channel supported strip 31. It will be seen that the conduit 22, fitting 23 and supporting strip 31 provide a simple and quickly installed means for leading the wiring to the light and for 25 supporting the light in the recess or chamber 19 and that, since the conduit 22 and fitting 23 are located on the rear side of the hollow arm with respect to the operator's position, they will not interfere with the operation of the machine. 30 Of course, the lamp socket 33 could be secured directly to the wall of the member 11 and within the recess or chamber 19, while the wires could pass therefrom through an opening into the member 11 and then downwardly within the interior of said member.

10 As previously set forth, the recess or chamber 19 in the underside of the horizontal member 12 extends longitudinally of the member 12 for a substantial distance and it is thus possible to 40 use a rather large and relatively long electric light bulb therein. Furthermore, since the recess or chamber is relatively long and the side walls 21 extend outwardly and downwardly from the arched portion of the underwall of the member 12, a maximum reflecting surface is provided and one that is substantially greater than that afforded by the usual reflecting shade, it being noted, at the same time, that the present construction is such as to not require the use of a 45 separate reflecting shade. The maximum reflecting surface offered by the walls of the recess or chamber and the ability to employ a relatively large electric light therein, together with the position of the recess or chamber on the 50 under side of the horizontal member of the arm, afford better illumination than is afforded by the usual lighting attachment for sewing machines and covers substantially the entire upper surface of the bed to the right of the vertical member 11, as viewed in the drawing.

10 As previously stated, the provision of the recess or chamber for the light within the under side of the horizontal member 12 of the arm results in the lighting means being located in a 55 position that does not interfere with the operation of the machine, and since the light and its socket are housed within the external dimensions of the horizontal member 12, fully protects the same against possible injury, particularly in machines of the drop head type.

10 It should furthermore be noted that there are practically no loose parts in the present construction, as compared to the lighting attachment heretofore used on sewing machines. The 75

outwardly and downwardly extending sides 21, in addition to furnishing a pleasing appearance to the machine, act as side shrouds to keep the light from shining into the eyes of the operator.

5 Although a preferred embodiment of the invention has been described and illustrated herein, it should be understood that the invention is susceptible of various modifications and adaptations within the scope of the appended claims.

10 Having thus described my invention, I claim:

1. In combination, in a sewing machine having a hollow bracket arm comprising a vertical member and a horizontal member, said horizontal member having means forming therein a recess separate from the interior thereof, a vertically extending conduit secured exteriorly of the vertical member and including a fitting at its upper end having a portion extending inwardly of the

inner side of said vertical member, a channeled strip secured to said portion and having its upper end arranged in said recess, and an electric lamp socket supported on said upper end of said strip.

2. In combination, in a sewing machine, a hollow bracket arm comprising a vertical member and a horizontal member, said horizontal member having integral portions forming therein on its under side a recess separate from the interior thereof, a conduit arranged exteriorly of the vertical member and including a fitting at its upper end having a portion lying adjacent to the inner side of said vertical member, a channeled strip secured to said portion of the fitting and having an end extending into said recess and provided with means for supporting an electric socket, and an electric socket arranged on said means.
